UNITED STATES PATENT OFFICE.

THEODORE P. BROWN, OF WORCESTER, MASSACHUSETTS, ASSIGNOR TO SIMPLEX PIANO PLAYER COMPANY, OF WORCESTER, MASSACHUSETTS, A CORPORATION OF MASSACHUSETTS.

PNEUMATIC MUSICAL INSTRUMENT.

No. 928,357.

Specification of Letters Patent. Patented July 20, 1909.

Application filed February 18, 1908. Serial No. 416,593.

To all whom it may concern:

Be it known that I, THEODORE P. BROWN, a citizen of the United States, residing at Worcester, in the county of Worcester and State of Massachusetts, have invented a new and useful Pneumatic Musical Instrument, of which the following is a specification.

This invention relates to a pneumatic action for auto-pneumatic musical instruments. Such instruments as usually constructed are provided with primary and secondary valves, the secondary valve being controlled from the primary valve and being of such a nature that it is necessary to adjust it and sometimes remove it and clean it in practice. These secondary valves give considerable trouble in the operation and many inventions have been made for the purpose of improving them to avoid or mitigate these difficulties.

The principal object of this invention is to do away with the secondary valve entirely and to provide a system of primary valves for controlling the striking pneumatics in a simple and efficient manner, thus avoiding all the disadvantages of the secondary valves and securing results equivalent to those secured by the use of the best forms thereof. This is brought about by the use of a double primary valve, both parts operating when air is admitted to the tracker channel which is connected to operate both of them, one acting at this time to shut off the striking pneumatic from communication with the outer air and the other to connect it with a source of suction. In this way, by the use of two of the ordinary simple primary valves, the complications and disadvantages of the secondary valves are avoided without employing any of the more complicated styles of secondary valves which have been devised.

Further objects and advantages of the invention will appear hereinafter.

Reference is to be had to the accompanying drawings which show a preferred embodiment of the invention and in which, Figure 1 is a plan of a tier of valve boxes and connections thereto. Fig. 2 is a longitudinal sectional view of the same on the line 2—2 of Fig. 1, and Fig. 3 is a sectional view on the line 3—3 of Fig. 2, so presented as to show both forms of pneumatics and their connections.

The device is shown as usual as comprising a front plate 10 having valve boxes 11 placed on the rear thereof in tiers. The tracker channels 12 extend down through the front plate in a well-known manner and terminate in a series of chambers in the valve boxes. A departure is made at this point from the ordinary construction as each tracker channel is provided with two branches in its valve box each leading to a separate chamber, designated respectively 13 and 14. Over each of these chambers there is a pouch 15, 16 similar to the ordinary primary pneumatic, above which is a suction chamber or passage 17 as is well understood. Each of the pouches supports a valve designated as 18 and 19 respectively. These valves are of well known types being adjustably mounted on their respective pneumatics or pouches and they are designed to control two passages 20 and 21, respectively. The valves are so constructed and set that when there is no impulse of air in the tracker channel, the pouches 15 and 16 being thus lowered, the valve 18 will close the communication between its passage 20 and the suction chamber 17 and open this passage to the outer air through a port 22. Under the same condition of affairs, the valve 19 falls so as to give a free communication between its passage 21 and the suction chamber 17 through a port 23 and to close the top of this port to prevent the admission of air to the passage 21.

The two passages 20 and 21 are provided with pouches 24 and 25 constituting a part of one wall of the same and not provided with valves but adapted to cover a pair of passages or conductors 26 and 27 extending from the striking pneumatic 28. The passages 26 and 27 are shown in the form of a pair of open ended tubes which will be closed when their respective pouches 24 and 25 are brought down upon their tops and opened when these pouches are raised. The end of the passage or tube 26 is in a suction chamber 30 while the passage 27 is open to the outer air. Now with the valves in the position shown in Fig. 3, it being understood that while this figure shows one primary of one valve box, and the other of another, yet these two primaries are shown in the positions that the two primaries of the same valve box would assume, the pressure of the air on the top of the pouch 24 forces it down

on the end of the tube 26 and closes the passage so that the striking pneumatic cannot communicate with the suction. On the other hand, the passage under which the tube 27 5 is located, being in communication with one of the suction chambers 17, this pouch is raised from the passage or tube 27 and the striking pneumatic is thus in communication with the outer air. Now if an air impulse is 10 admitted into the tracker channel, which is done in the usual way, the two pneumatics 15 and 16 will be raised taking the valves 18 and 19 with them. This cuts the passage 20 off from the outer air and puts it into communication with the suction chamber 17 and 15 has the opposite effect on the passage 21. Consequently, the pouch 24 will be raised and the pouch 25 will be allowed to drop, there being the same pressure on both sides 20 of the latter.

It will be noted that the suction in the passage 20 operates over the entire upper surface of the pouch 24 and the suction in the chamber 30 operates only on that surface 25 outside the tube 26 when the pouch is resting thereon; consequently the pouch will now be raised. After this condition of affairs is established, the flow of air out of the striking pneumatic over the top of the tube 26 30 will keep the pouch up from the tube as long as this condition is allowed to exist. At the same time, the flow of air from the tube 27 through the striking pneumatic to the tube 26 will draw the pouch 25 down on the top 35 of the tube 27 and prevent the admission of air thereto.

The suction chambers 17 communicate with the tracker channels 12 through passages 31 which are covered by disks 32 each 40 provided with a pin-hole perforation for bleeding purposes. Opposite each of the channels 31 is a screw-threaded opening in which is located a screw 320 which can be removed to permit access to the bleeding disk 45 for the purpose of cleaning any dust out of the perforation therein. It will be seen, therefore, that all the advantages of the secondary valves, even of the best make, are secured by this invention while their disadvantages 50 are avoided as the simple pouches which are substituted for them are of such a character that they will not require any cleaning or adjustment or in fact any attention whatever. They work regularly, positively and automatically and their durability 55 is much greater than any secondary valve which has yet been proposed.

While I have illustrated and described a preferred embodiment of the invention, I am 60 aware that many modifications may be made therein by any person skilled in the art, without departing from the scope of the invention as expressed in the claims. Therefore, I do not wish to be limited to the particular form shown, but

What I do claim is:—

1. In a musical instrument, the combination with a striking pneumatic, of a tracker channel, two chambers communicating directly with the tracker channel, a pneumatic 70 located in each of said chambers, a valve operated by each of said pneumatics, means controlled by one of said valves for admitting air to the striking pneumatic, and independent means controlled by the other valve 75 for exhausting the striking pneumatic.

2. In a musical instrument, the combination with a striking pneumatic, of a tracker channel, two chambers communicating directly with the tracker channel, a pneumatic 80 located in each of said chambers, a valve operated by each of said pneumatics, a diaphragm or pouch controlled by one of said valves for admitting air to the striking pneumatic, and independent means controlled by 85 the other valve for exhausting the striking pneumatic, and comprising a passage having an open end and a diaphragm or pouch for closing the passage.

3. In a musical instrument, the combination with a striking pneumatic, of a tracker channel, two primary pneumatics both in direct communication with said tracker channel, and two pouches, each controlled by one of said primary pneumatics, for conjointly 95 controlling the operation of the striking pneumatic.

4. In a musical instrument, the combination with a striking pneumatic and a suction chamber, of a tracker channel, two pneumatics 100 communicating with the tracker channel, valves operated by said pneumatics, means controlled by one of said valves for admitting air to the striking pneumatic, and means controlled by the other valve for connecting the striking pneumatic with the suction chamber.

5. In a musical instrument, the combination with a tracker bar channel, of two pneumatics connected therewith, a valve 110 controlled independently by each of said pneumatics, one of said valves being arranged to close and the other to open when an impulse passes through the tracker channel, a striking pneumatic and means controlled by said valves for operating the striking pneumatic.

6. In a musical instrument, the combination with a tracker bar channel, of two primary pneumatics connected therewith, a primary valve controlled by each of said pneumatics, a striking pneumatic and means controlled by said valves for operating the striking pneumatic, said means comprising two pouches, each connected with and controlled by one of said valves and one constituting means for admitting air to the striking pneumatic and the other for connecting the striking pneumatic with a source 125 of suction.

7. In a musical instrument, the combina- 130

tion of a tracker channel, a suction chamber, two primary pneumatics separating the suction chamber from the tracker channel, a valve connected with each of said pneumatics, two passages, each controlled by one of said valves, one of the valves being normally in position to admit air to its passage and the other to connect its passage with the suction chamber when the tracker channel is closed and under suction, and means connected with said passages for controlling a striking pneumatic.

8. In a musical instrument, the combination with a striking pneumatic, of an open-ended tube projecting therefrom, a suction chamber surrounding the end of the tube, a pouch of larger diameter than the tube located at the end of the tube and adapted to close it and forming a wall of said suction chamber, and a chamber on the side of the pouch opposite said suction chamber adapted to be put under suction to move the pouch from the end of the tube.

9. In a musical instrument, the combination with a striking pneumatic, of an open-ended passage extending therefrom, a suction chamber surrounding the end of the passage, a pouch of larger diameter than the passage located at the end of the passage

and adapted to close it and forming a wall 30 of said suction chamber, a chamber on the side of the pouch opposite said suction chamber adapted to be put under suction to move the pouch from the end of the passage, and means for admitting air to the striking pneumatic whenever the pouch closes said passage, whereby the area of the pouch in communication with said chamber is greater than that in communication with said suction chamber. 40

10. A device for controlling the connection of a striking pneumatic with the outer air, comprising a primary valve, a passage controlled by said valve, a pouch constituting a wall of said passage, a striking pneumatic, and a tube projecting from the striking pneumatic and opening into the outer air and adapted to be closed by said pouch when air is admitted by said valve into said passage, and to be opened when the passage 50 is put under suction.

In testimony whereof I have hereunto set my hand, in the presence of two subscribing witnesses.
